UNITED STATES PATENT OFFICE

CLARENCE N. GRINNELL, OF COLLINGSWOOD, AND WILLIAM B. STEVENSON, OF MOORESTOWN, NEW JERSEY, ASSIGNEES TO RADIO CORPORATION OF AMERICA, A CORPORATION OF DELAWARE

DESIGN FOR A RADIOCABINET

Application filed February 16, 1933. Serial No. 47,236. Term of patent 7 years.

To all whom it may concern:

Be it known that we, CLARENCE N. GRINNELL, a citizen of the United States, and a resident of Collingswood, in the county of Camden and State of New Jersey, and WILLIAM B. STEVENSON, a citizen of the United States, and a resident of Moorestown, in the county of Camden and State of New Jersey, have invented a new, original, and ornamental Design for Radiocabinets, of which

the following is a specification, reference being had to the accompanying drawing, forming a part thereof.

The figure is a perspective view of a cabinet embodying our new design.

We claim:

The ornamental design for a radiocabinet substantially as shown.

CLARENCE N. GRINNELL.
WILLIAM B. STEVENSON.
